United States Patent Office

Des. 206,192
Patented Nov. 8, 1966

206,192

DIAPER BAG

Mary Hagglund, 921 Chambers, Ottawa, Ill.

Original design application Apr. 20, 1964, Ser. No. 79,584, now Patent No. 202,381, dated Sept. 21, 1965.
Divided and this application May 5, 1965, Ser. No. 85,839

Term of patent 14 years

(Cl. D58—2)

FIG.1

This is a division of design patent application, Serial No. D.79,584 filed April 20, 1964 and now Patent Number D.202,381 issued September 21, 1965.

I claim:

The ornamental design for a diaper bag, substantially as shown and described.
